UNITED STATES PATENT OFFICE.

EDMOND L. BRUNSWICK AND HARRY CHRISTENSEN, OF CHICAGO, ILLINOIS.

DESIGN FOR A LIGHT FIXTURE.

Application filed December 31, 1921. Serial No. 526,401. Term of patent 3½ years.

To all whom it may concern:

Be it known that we, EDMOND L. BRUNSWICK and HARRY CHRISTENSEN, citizens of the United States, residing at Chicago, in the county of Cook and State of Illinois, have invented a new, original, and ornamental Design for a Light Fixture, of which the following is a specification, reference being had to the accompanying drawing, forming part thereof.

Figures 1 and 2 are, respectively, front and side elevational views of a light fixture showing our new design.

We claim:

The ornamental design for a light fixture as shown.

In witness whereof, we hereunto subscribe our names this 28th day of December, 1921.

EDMOND L. BRUNSWICK.
HARRY CHRISTENSEN.

Witnesses:

EDNA V. GUSTAFSON,
ALBIN C. AHLBERG.
